UNITED STATES PATENT OFFICE.

GEORGE J. COMNINOS, OF PITTSBURGH, PENNSYLVANIA.

GAS-BURNER.

1,123,489.

Specification of Letters Patent.

Patented Jan. 5, 1915.

Original application filed April 8, 1914, Serial No. 830,377. Divided and this application filed September 16, 1914. Serial No. 862,002.

To all whom it may concern:

Be it known that I, GEORGE J. COMNINOS, a subject of the King of Greece, and residing in the city of Pittsburgh, in the county 5 of Allegheny and State of Pennsylvania, have invented or discovered new and useful Improvements in Gas-Burners, of which the following is a specification.

This application is a division of my previous 10 patent application filed April 8th, 1914, Serial Number 830,377.

My present invention relates to burners for gas stoves, heaters and furnaces, and the object in view is to preheat the fuel before 15 it is admitted to the perforated burner face, thereby expanding the same, improving its burning qualities and insuring its uniform distribution.

The objects are accomplished by me by 20 providing within the burner a baffle which depends from the top of the former to within a relatively short distance from the bottom thereof. The said baffle is preferably nearer the perforated burner face 25 than to the rear wall of the burner thus forming a larger compartment adjacent to the rear wall of the burner and a smaller compartment adjacent to the burner face. The gas is admitted to the larger compartment 30 at a point above the lower edge of the baffle.

In the accompanying drawings, which illustrate my invention applied to an annular gas burner, Figure 1 is a vertical section 35 of the burner taken along the line I—I in Fig. 2, while Fig. 2 is a section of the same taken along the line II—II in Fig. 1.

The following is a detailed description of the drawings.

The burner is of annular form comprised 40 of an outer vertical wall 1 having a plurality of gas perforations 2; an inner or rear wall 3; a top wall 4 and a bottom wall 5, all secured together with gas tight joints 45 so that the only escape for the gas is through the perforations 2 where the gas is ignited and burns as jets in the usual manner.

Within the burner and depending from 50 its top 4 is an annular baffle 6 which extends down to a point a relatively short distance from the bottom 5, thus leaving a port

7. The baffle 6 is nearer the front wall 1 than the rear wall 3 so that the compartment *a* in front of the baffle is of less capacity than the compartment *b* in the rear of said baffle. A gas pipe 8 leads up through the bottom 5 and discharges in the rear compartment *b* at some distance above the port 7 beneath the baffle 6. When the 55 burner is in use, the gas is admitted through the pipe 8 into the compartment *b* and is heated therein, expanding and being distributed at substantially uniform pressure through the length of said compartment. 60 The gas is forced down underneath the baffle 6 into the compartment *a* wherein it rises and escapes in jets through the perforations 2. The gas is heated and thus is more readily and thoroughly consumed, 65 70 reducing the amount of waste products of combustion. Also the supply of gas for the full extent of the chamber *a* is of uniform pressure so that the entire perforated wall 1 is evenly supplied. 75

What I desire to claim is:—

1. A gas burner for the purpose described comprising an inclosed annular body having its outer wall perforated for the escape of gas in jets; an annular baffle wall depending within said body from the top thereof and dividing said body into two annular compartments communicating at the bottom, and means for admitting gas to the inner compartment above the lower 85 edge of said baffle wall.

2. A gas burner for the purpose described comprising an inclosed annular body having its outer wall perforated for the escape of gas in jets; an annular baffle wall depending within said body adjacent to said outer wall and dividing said body into two compartments, the inner compartment being of greater capacity and said compartments communicating at the bottom, and means 90 for admitting gas to said inner compartment above the lower edge of said baffle wall. 95

Signed at Pittsburgh, Penna., this 14th day of September, 1914.

GEORGE J. COMNINOS.
